UNITED STATES PATENT OFFICE

OWEN M. NACKER, OF PLEASANT RIDGE, MICHIGAN, ASSIGNOR TO GENERAL MOTORS CORPORATION, OF DETROIT, MICHIGAN, A CORPORATION OF DELAWARE

IGNITION COIL MOUNT

Application filed June 14, 1930. Serial No. 461,069.

This invention relates to motor vehicles or the like, and particularly to an improvement in the arrangement and location of parts of a conventional ignition system for internal combustion engines.

The invention aims to provide for the mounting of the coil box in an easily accessible position, to facilitate assembly and subsequent inspection and repair, and in convenient proximity to the usual distributor mechanism, to make possible the use of short lead wires between the coil and distributor, which in addition to reducing costs materially enhances the general appearance of the assembly.

The invention also contemplates the removal of the coil, as far away as possible from the vehicle body, for the purpose of reducing interference to radio reception in those cases where the vehicle is equipped for radio communication.

A further and important object is to so locate the coil as to save it from the harmful effects of intense and excessive heat conditions that sometimes prevail near the engine and beneath the engine hood.

It is proposed, according to a preferred embodiment of the engine, to mount the coil box adjacent the top of the usual radiator that forms part of the engine cooling system, and preferably with at least a portion thereof projecting into a pocket formed in the rear wall of the top header or tank of the radiator structure. In this fashion the maximum temperature, to which a coil is subjected, is greatly reduced, the temperatures being less than 212° F. at all times, and more generally around 160° F. as compared with temperatures often exceeding 300° F. at high speed on a summer day, to which a coil is subjected when mounted near the engine and under the hood in the usual manner, and which extreme temperatures have been the cause of frequent coil failures in the past.

A better understanding of the nature of the invention will be had upon reference to the accompanying drawings illustrating a preferred embodiment incorporated as standard construction in the Cadillac V-16 automobile, and wherein Figure 1 is a top plan

view of an engine and its associated parts; Figure 2 is an elevation, looking in the direction of the arrows on line 2-2 of Figure 1, and Figure 3 is a sectional view taken on line 3-3 of Figure 2.

Referring to the drawings, the numeral 1 indicates an internal combustion engine having two banks or rows of cylinders arranged in angular or V relation, and being mounted in any suitable fashion in the usual chassis frame forward of the dash board 2 of the vehicle body. This engine is jacketed for the circulation of water or other cooling medium, to absorb the heat of combustion, and the jackets communicate with a cooling radiator, forming a part of the engine cooling circuit, where the heat is dissipated as it passes through the radiator. As usually constructed, the radiator comprises a pair of spaced tanks and an intermediate core or heat dissipating unit, through which water flows from tank to tank, Figure 3 showing a fragment of the core unit, which is indicated at 4, and the upper tank or inlet header 5. For appearance purposes, the radiator structure is incased in an ornamental shell or housing 6, shown as being provided at its rear edge with a depressed portion 7, that forms a ledge or rest for the forward end of the engine bonnet or hood (not shown). In the present case, the radiator structure is provided with an additional appearance shell or member 9, secured at its forward end to the hood ledge 7, and covering the rear face of the upper tank 5, and if desired, projecting downwardly along the sides of the main shell 6, to afford a finished appearance to the radiator structure.

At its upper central portion, the appearance member 9 has secured thereto a bracket 11, having a rearwardly projecting ear or lug 12, through which extends a pivot pin or fastening stud 13, for securing thereto the forward ends of a pair of divergent tie rods 14. These rods 14 extend rearwardly above the engine with their rearward ends projecting through the dash board 2, and carrying screw threads for adjustable attachment to the dash board, as by means of nuts 15, threaded thereon. The angular relation of

the tie rods serves to effectively brace the top portion of the radiator against movement in all directions, and the adjustable connections between the rods 14 and dash board 2, permits slight variations in the relative position of the radiator to effect a proper and neat fitting of the engine hood and alignment of the several associated parts.

In addition to their function of bracing the radiator, the tie rods 14, which may be formed of hollow tubing or the like, provide conduits for the passage of electric wires or current conductors leading to or from a point within the body of the vehicle, for connection, as for example, with a switch or indicator mounted on the customary instrument panel. In the drawings, such wires are indicated by the reference numeral 17 and they may constitute a part of the engine ignition system which is shown as including a pair of coil boxes 18, and an engine driven distributor 19, located on top of the engine at the front end thereof.

It will be understood that one or more coils may be utilized, depending upon the character of the ignition system, and the coil enclosing box or boxes may be located just above the distributor 19, and mounted on the radiator structure. According to Figure 2, use is made of the bracket 11 for securing the coil boxes in place, and for this purpose the bracket is provided with a pair of spaced openings or eyes, defined by forwardly projecting annular flanges 22, the flanges of the two openings being split at points adjacent each other, with corresponding ends connected by a pair of webs 23 and 24. Aligned openings are provided in the two connecting webs 23 and 24, to receive a screw stud 25, and one of the openings may be threaded to receive the threads of the screw stud, so that upon adjustment of the stud the rings can be contracted about the coil boxes, with the forward ends of the rings in engagement with an annular locating bead 27 of the boxes, whereby each box is positively clamped in proper position.

To prevent the action of excessive heat on the coils, the upper header or radiator tank 5, is extended rearwardly as at 30, and the rear wall of the extension is provided with a pair of depressions as at 31, in registry with the openings in the bracket 11, to form pockets that receive the forwardly projecting portions of the coil boxes. In this manner the major portion of each coil extends into a depression in the upper header and is thus protected from the intense heat, such as would cause it to deteriorate and break down. The construction so afforded also lends a neat and pleasing appearance to the engine compartment, with only the heads of the coil boxes exposed to observation, and these being located in close proximity to the distributor to permit the use of short wires leading to the distributor, with the current conductors lead-

ing to the ignition coils concealed in the tie rods.

While the invention has been specifically described in its preferred embodiment, it will be understood that various modifications can be readily made, as will be apparent to those skilled in the art, without departing from the spirit and scope of the appended claims.

I claim:

1. In a motor vehicle, an engine having an ignition system and a cooling system, a radiator forming a part of the cooling system, a device forming a part of the ignition system and means to mount said device in a portion of the radiator.

2. In a motor vehicle, a cooling radiator having a pocket therein and an ignition device located within said pocket.

3. In a motor vehicle, a radiator forming a part of an engine cooling system and having a tank, a pocket in said tank and an engine ignition device in said pocket.

4. In a motor vehicle, a radiator forming a part of an engine cooling system and having a tank, a depression in one wall of said tank, an ignition device and means to mount said device in said depression.

5. In a motor vehicle, an engine having a cooling system, and an ignition system, a coil forming a part of the ignition system, and means to utilize cooling fluid in said system to prevent excessive temperatures at said coil.

6. In a motor vehicle, a radiator having a tank, a depression in one wall of the tank, a bracket carried by the radiator and provided with a split ring portion, means to contract said ring, and an ignition coil adapted to be secured in said contractile ring with a portion thereof projecting into said depression.

7. In a motor vehicle, a radiator having a tank provided with a pair of cupped portions projecting into the tank from one wall thereof, a bracket having a pair of openings aligned with said cupped portions, and a pair of ignition devices carried by the bracket in said openings with portions thereof extended into said cupped portions.

8. In a motor vehicle, a radiator provided with a pocket projecting into a tank thereof, an appearance member positioned beside the radiator and an ignition device carried by said member with a portion thereof projected into said pocket.

9. In a motor vehicle, a radiator having a top tank provided with a pocket projected into the tank from one wall thereof, an ignition device extending into said pocket, and a hollow tie rod forming a combined radiator brace and conduit for concealing current conductors connected with said ignition device.

10. In a motor vehicle, a radiator, an ignition device adjacent the radiator, and a

hollow brace rod for the radiator adapted to contain electric cables for connection with said ignition device.

11. In a motor vehicle, an engine having an ignition system and a cooling system, a radiator forming a part of the cooling system, a device forming a part of the ignition system, and means to mount said device on the radiator.

10 12. In a motor vehicle, an engine having a cooling system and an ignition system, a coil in said ignition system, and means in the cooling system to receive said coil to directly affect the temperature thereof.

15 In testimony whereof I affix my signature.
OWEN M. NACKER.
